COIN COUNTING TRAY

Lewis T. Lanier, P.O. Box 1367, Concord, N.C., assignor
of fifty percent to Melick W. Blades, Apex, N.C.

Filed Sept. 10, 1963, Ser. No. 76,538

Term of patent 14 years

(Cl. D52—4)

FIGURE 1 is a perspective view of my coin counting tray looking down on one surface;

FIGURE 2 is another perspective view looking up at the other surface of my coin counting tray; and

FIGURE 3 is an end elevation of my coin counting tray with the tray being inverted from the position shown in FIGURES 1 and 2.

I claim:

The ornamental design for a coin counting tray, substantially as shown.
